Primary Examiner — L. Martinez(74) *Attorney, Agent, or Firm* — Russ Weinzimmer & Associates, P.C.(57) **CLAIM**

The ornamental design for a wine glass necklace, as shown and described.

DESCRIPTION

FIG. 1 is a front isometric view of a wine glass necklace showing my new design.

FIG. 2 is a detailed side perspective view thereof, taken from FIG. 1.

FIG. 3 is a rear isometric view thereof.

FIG. 4 is another detailed side perspective view thereof, taken from FIG. 3; and,

FIG. 5 is another front isometric view of the wine glass necklace in FIG. 1, showing my new design in a configuration of use.

The broken lines in the drawings illustrate environmental subject matter only and form no part of the claimed design.

1 Claim, 3 Drawing Sheets(56)
